The Adlake Company, Chicago, Ill., a corpora-
tion of Illinois

Application November 11, 1935, Serial No. 59,482

Term of patent 14 years

To all whom it may concern:

Be it known that I, Hugh H. Hendrickson, a citizen of the United States, residing at Elkhart, in the county of Elkhart and State of Indiana, have invented a new, original, and ornamental Design for a Metal Sash Rail, of which the following is a specification, reference being had to the accompanying drawing, forming a part there-

In the drawing,

Fig. 1 is a perspective view of a section of a sash rail showing my design; and
Fig. 2 is an end view thereof.

I claim:

The ornamental design for a metal sash rail, substantially as shown.

HUGH H. HENDRICKSON.
